UNITED STATES PATENT OFFICE

121,154

DESIGN FOR A CONTAINER SERVER TOP OR SIMILAR ARTICLE

Rudolph Bernhardt, Chicago, Ill.

Application February 4, 1939, Serial No. 82,786

Term of patent 3½ years

To all whom it may concern:

Be it known that I, Rudolph Bernhardt, a citizen of the United States and resident of Chicago, in the county of Cook, and State of Illinois, have invented a new, original, and ornamental Design for a Container Server Top or Similar Article, of which the following is a specification, reference being had to the accompanying drawing, forming part thereof.

In the drawing, Figure 1 is a perspective view of a container server top or similar article, showing my new design;

Figure 2 is a side elevational view of the same; Figure 3 is a front elevational view; and Figure 4 is a top plan view.

The characterizing feature of the design resides in the container server top of the configuration shown having a unitary handle of the same thickness as the cap portion of the article throughout its length, said handle being rounded outwardly and downwardly from the cap portion and flush with the upper surface of said cap portion, as shown.

I claim:

The ornamental design for a container server top or similar article, as shown and described.

RUDOLPH BERNHARDT.
